UNITED STATES PATENT OFFICE

125,719

DESIGN FOR A TEXTILE FABRIC

Benjamin Frank, New York, N. Y.

Application February 12, 1941, Serial No. 98,956

Term of patent 3½ years

To whom it may concern:

Be it known that I, Benjamin Frank, a citizen of the United States, residing at Manhattan, county of New York, and State of New York, have invented a new, original, and ornamental Design for a Textile Fabric, of which the following is a specification, reference being had to the accompanying drawing, forming part thereof, wherein the figure is a plan view of a textile fabric showing my new design.

I claim:

The ornamental design for a textile fabric, substantially as shown.

BENJAMIN FRANK,
